UNITED STATES PATENT OFFICE.

ELLIS F. EDGAR, OF WOODBRIDGE, NEW JERSEY.

VAPOR GENERATOR AND BURNER.

SPECIFICATION forming part of Letters Patent No. 469,685, dated March 1, 1892.

Application filed November 23, 1887. Serial No. 255,970. (No model.)

To all whom it may concern:

Be it known that I, ELLIS F. EDGAR, a citizen of the United States, residing at Woodbridge, in the county of Middlesex and State of New Jersey, have invented a new and useful Improvement in Vapor Generators and Burners, of which the following is a specification, reference being had to the accompanying drawings, forming part of the same, in which—

10 Figure 1 is an upper face view of my apparatus. Fig. 2 is a cross-sectional view thereof on line $x-x$, Fig. 1. Fig. 3 is a longitudinal vertical section of the vaporizing-vessel, but representing, in addition, an auxiliary reservoir, a connection between it and the apparatus in question, and a special valve. Fig. 15 4 is an enlarged vertical sectional view of said valve. Fig. 5 is a perspective view of said apparatus from which a section has been cut on line $x-x$, Fig. 1. Fig. 6 is a longitudinal vertical section of the vaporizing-vessel, showing the vapor-burner in elevation. Fig. 20 7 is a bottom view of the construction of Fig. 6. Fig. 8 is a perspective view of a stove, in which one of the herein-described apparatus 25 is placed, parts being broken away to show its features more clearly.

My invention relates to that class of apparatus in which the combustion of oil or kindred material is accomplished (primarily at least) for the production of heat; and it consists of a reservoir for holding said material in its ordinary state provided in its top with apertures leading therefrom to the outer air 35 above it, and in the combination therewith of various devices and attachments, as herein-after described and claimed.

Various methods of burning oil from the surface of a material which had absorbed it 40 and in various other ways have been devised; but they are substantially all open to the objection that the combustion does not approach perfection and smoke is produced to the consequent loss in heat developed, and the consequent annoyance of soiling articles brought 45 in contact therewith; and to obviate this objection is one of the purposes of my invention. In carrying out the same in its preferable form I mold a vessel of fire-clay or other in- 50 combustible material, (the apparatus shown,) 50

its rectangular form being best adapted for use in the fire-box of stoves, where it is principally used. It is provided internally with an open space A, called the "reservoir," which is its principal feature, and which is surrounded by side walls a , end walls b , and a covering-wall c . This covering is pierced with a large number of minute holes e and a larger one E, through the latter of which the reservoir may be filled, it being thereafter tightly closed. 55 The end walls b not only inclose the reservoir, but extend beyond the side walls thereof for a distance on either side, and these extensions are connected by longitudinal walls b' , running from one end wall to the other parallel to the side walls of the reservoir, but separate therefrom, except at the center, where said longitudinal walls and side walls form one piece, or, as it were, a bridge b^2 , as seen in Fig. 2, to increase the strength of the apparatus. 60 The walls b' and the extensions of b may be dispensed with; but they add great advantages, as will readily appear. The interior surfaces of said walls b' are preferably beveled outwardly from top to bottom, as seen 65 in Fig. 2, for a purpose presently to be named.

The operation of this apparatus is as follows: Oil or equivalent material is introduced into reservoir A, usually through opening E, until it is about half-filled, though, if filled, it 70 will soon be less than full and will operate as it will if less than half-filled. This material at once begins to percolate through the pores in the lower portions of walls a and will soon collect upon the exterior thereof. It is then 75 ignited and burns freely up about the sides of A, greatly assisted by the draft caused by the rush of air and flame through the passages p between walls a and b' . The heat produced by the fire thus produced speedily converts a 80 portion of the material within the reservoir into vapor, which rushes through apertures e , is ignited above them by the flame issuing through passage p , and the united combustion produces a great, yet economical, heat, the 85 results obtained being far superior to those produced by the direct burning of oil.

To effect a complete combustion of the materials employed, the combination therewith of large quantities of air is necessary, and this 90 95

I accomplish through the agency of the passages *p*. The flame of the material oozing through *a* heats the air in these passages and of course it ascends, *p* acting as chimneys, 5 and I have made them narrower at the top than bottom, that ample air might be furnished at the point of primary combustion, that its motion might be accelerated, and that the flame and air issuing from the upper ends 10 of said passages may be so directed as to impinge at once upon the currents of gas issuing from *e*. The result is great economy and cleanliness in the consumption of oil and kindred materials for heating purposes, especially when the apparatus is used in the fire- 15 box of a stove. To produce the best results when so located, no space should be left for the passage of air through the fire-box between its walls and *b'* or *b*, but all the air be compelled 20 to pass through *p*, as better draft thereby results, and it may be better controlled by the usual dampers of the stove, though, if preferred, dampers may easily be arranged within or at either opening of *p*. Its application to a 25 stove is fully shown in Fig. 8, with this variation: that as the stove is provided with a water-back *w* the side wall *b'*, which would be on that side if the apparatus were placed in the stove without change, has been removed, 30 and the water-back itself acts as a wall to form with the side *a* adjacent to it the passage for air. This arrangement insures the heating of the water in the boiler *B*, connected to the water-back by pipes *n* and *m*, 35 for the flame touches the surface of said water-back in passing upward. It also enables me to dispense with one side wall, as will readily be seen, for the end walls *b* and the bridge *b'*, resting upon the grate *g* of the 40 stove *S*, amply support the reservoir in proper position. At the rear side of course the draft must be through passage *p*, for there is no other, and at the front the same result is attained by packing the space between *b'* and 45 *f* (the stove-lining or ordinary brick) with asbestos *d* or any other suitable filling, and thus forcing the air to pass through *p* on its way from the front openings in the stove to the pipe *H* and the chimney. The apertures 50 *e* should be small enough to prevent any possibility of the flame backing through them to the reservoir *A*, and I have found that with the covering-wall *c* three-quarters of an inch thick and said apertures about one thirty- 55 second of an inch in diameter such result will be accomplished. So, too, the apertures through the walls *a*, if an apertured material is used, should be small enough to insure that no flame will pass through them into *A*, but 60 will be sure to pass up and around the outside of said walls *a*. Any porous material almost has pores small enough to accomplish this.

In Figs. 6 and 7 is shown a pipe *p'*, extending from the vapor-space of the vaporizing chamber or vessel *A* to and along be-

neath the bottom of said vessel, and is provided with a vapor-burner beneath said bottom or is formed into a burner by means of perforations through its upper side, a portion 7c of the vapor generated passing from the vapor-space of the vessel *A* through the pipe *P'* and burning at the vapor-burner located beneath the bottom of said vessel, thereby increasing the heat.

One charge of oil will last for a considerable time; but if it is desired to burn a continuous fire in this apparatus it may easily be done by connecting thereto an auxiliary reservoir *A'*. This may be done by means of 80 an ordinary supply-pipe *s*, passing through the opening *E*. I prefer to extend it onto or near the bottom of the reservoir, and to provide it with an automatic valve *V*, as shown, which will keep the liquid in the primary 85 reservoir *A* at an even level without constant attention. This valve I construct as follows: The lower portion of *s* is cut away or left open to permit free passage for the liquid. Some distance above the said lower end I place a dia- 90 phragm *v*, with a small reverse V-shaped aperture through it. Below said aperture I place one or two bridges *v'*. Through said bridge or bridges I pass a stem *v*², which is sustained in proper line thereby. Its upper end bears an enlargement *v*³, adapted when raised to close the aperture in *v*, and upon said stem I fasten a float *f*, preferably having the contour and nearly the diameter of *s*.

The operation is obvious. Liquid entering 100 through *s* passes into *A* and rises until its pressure lifts the float *f*, stem *v*², and valve *v*³, which closes the aperture *v* and prevents further entry of liquid until the level thereof in *A* is slightly reduced, when the float descends, 105 the valve opens, and liquid enters to restore the predetermined level. Of course other forms of valve might be used to accomplish this same purpose and their combination with apparatus such as specified would be within the 110 spirit of my invention.

What I claim as my invention, and desire to secure by Letters Patent, is—

1. A hydrocarbon-fluid vaporizer and burner consisting of a non-combustible porous vessel 115 provided with vapor-escape openings located in its top and side walls integral with said vessel, forming therewith tapering channels, in combination with means for supplying oil to said vessel, and a burner-pipe communicating with said vessel and extending around beneath the same, substantially as described.

2. A hydrocarbon-fluid vaporizer and burner consisting of a non-combustible porous vessel 120 provided with vapor-escape openings located in its top and side walls integral with said vessel, forming therewith tapering channels, and means for supplying oil to said vessel, substantially as described.

3. An oil vaporizer and burner consisting 125 of a closed vaporizing-retort formed of porous non-combustible material provided with an

oil-supply and vapor-escape openings in its upper portion, whereby the oil contained in said vessel percolates through and to the exterior of the bottom thereof and is adapted to burn thereon and vaporize the oil in the vessel, and a burner-pipe opening into the upper portion of the retort and extending beneath

the retort and provided with a burner, substantially as described.
